UNITED STATES PATENT OFFICE.

CHARLES TRUELOVE AND WILLIAM T. HAIGHT, OF CHARLESTON, WEST VIRGINIA,
ASSIGNORS TO THE LIBBEY-OWENS SHEET GLASS COMPANY, OF TOLEDO, OHIO, A
CORPORATION OF OHIO.

BENDING ROLLER FOR DRAWN SHEET GLASS.

Application filed February 4, 1924. Serial No. 690,392.

This invention relates to improvements in the art of drawing sheet glass, and more particularly to an improved form of bending roller about which the plastic glass sheet is deflected from one plane into another.

In the system of drawing sheet glass disclosed in the patent to Colburn, 1,248,809, granted December 4, 1917, a sheet of glass is drawn vertically upward from a shallow pool of molten glass, and then while still plastic is bent about a cylindrical roller into the horizontal plane where it is flattened and carried away through a leer as a continuous strip or ribbon of glass. In order to continuously maintain the width of the sheet, and otherwise improve the quality of sheet produced, each edge of the sheet directly above the molten source passes between a pair of cooled, knurled, rollers, which are positively driven at a peripheral speed considerably less than the linear speed at which the sheet is drawn upward. These cooled rollers grip and hold back on the edge portions of the sheet, and serve to stiffen and place an added tension on these edge portions, the result being to keep the sheet to a uniform width. The edge portions of the sheet of glass will be roughened and somewhat thicker than the main central portion which will have smooth highly polished surfaces and be of a uniform thickness.

Since the edge portions of the sheet are initially retarded by the knurled rollers, the different portions of the sheet will travel at different speeds in their vertical run up to the bending roller. All portions of the sheet should pass around the roller at about the same linear speed, but in order to attain this speed the cooled edge portions, which are given a delayed start, must travel faster than the central portion during this vertical run. Due to this initial variation in speeds between the edge portions and the central portion of the sheet, and the fact that the edge portions are cooler and usually thicker than the central portion, there will sometimes be a difference in linear speed between the edges and the central portion while the sheet is passing about the bending roller. This will necessitate slippage of some portions of the sheet on the roller surface and there will consequently be a liability of scratching or wrinkling the sheet during this bending operation.

According to the present invention those portions of the bending roller which carry the edge portions of the sheet are made in the form of freely rotatable sleeves set into the body of the bending roll proper, whereby the edge portions of the sheet are allowed to proceed at a somewhat different rate than the central portion of the sheet during this bending operation. This will relieve the sheet from any undue strains at this point and will greatly diminish or eliminate the scratching and wrinkling of the sheet referred to above.

The objects and advantages of the invention will be better understood from the following detailed description of certain approved forms of the apparatus.

In the accompanying drawings:

Fig. 1 is an elevation of that portion of the sheet-drawing mechanism comprising the improved bending roller, the receptacle for the pool of molten glass being shown in transverse vertical section.

Fig. 2 is a central vertical section on an enlarged scale through one end of the bending member.

Fig. 3 is an elevation of one end of a modified form of roller, also embodying some of the principles of this invention.

The glass sheet 1 is drawn upwardly from the pool of molten glass 2 in receptacle 3. After the sheet has been drawn upwardly till it has assumed approximately its final sheet form, but is still somewhat plastic, it is bent about the bending roller 4 into the horizontal plane. The sheet is then drawn away through suitable drawing and flattening mechanism and thence into the annealing leer. The drawing and flattening mechanism is not here illustrated, but may be of the type disclosed in the Colburn patent referred to hereinabove. Each edge of the sheet, adjacent its source passes between a pair of knurled or roughened rollers indicated at 5. These rollers are internally cooled, and are slowly driven at a peripheral speed considerably less than the linear speed at which the sheet is drawn upwardly. These rollers and the driving mechanism therefor, are described more in detail in the Colburn patent referred to above. The edge portions 6 of sheet 1 will be marred or roughened by the gripping action of rollers 5, but these edges are eventually cut away and discarded. These edge portions 6 will

draw somewhat thicker than the main body portion of sheet 1 and will be cooler and stiffer due to the contact therewith of the internally cooled rollers 5.

6 The bending roller 4 is made of some suitable alloy, such as Monel metal or nichrome, capable of taking and maintaining a high polish on the cylindrical surface 7 upon which the glass sheet is carried during the 10 bending operation. Adjacent each end a separate sleeve member 8 is inset into the surface of cylinder 4 so that the outer sheet-carrying surface of sleeve 8 is substantially a continuation of the cylindrical surface 7 of the roller. In order to permit the insertion 15 of this sleeve 8, roller 4 may be made of telescoping parts screwed together as at 9, and roller bearings 10 are preferably used between the sleeve 8 and the supporting portion 20 of roller 4. The sheet-carrying surface of sleeve 8 is preferably grooved or knurled as indicated at 11 to positively grip the roughened edge portions 6 of the glass sheet and hold the sheet against lateral contraction 25 while passing around the bending member.

While means are usually provided to drive the roller 4, to assist in beginning the sheet-drawing operation, ordinarily this roller 4 turns idly in roller bearings when the drawing 30 operation is once under way. The roller 4 will then be rotated by the frictional contact of the glass sheet 1 bearing on the polished cylindrical surface 7. Since the sleeves 8 are also freely rotatable with respect to the 35 main body portion of roller 4, the edge portions 6 of the sheet which are carried by the sleeves 8 may rotate either faster or slower than the main portion of the sheet, thus relieving the sheet from any unnecessary 40 strains and eliminating the necessity for slippage of the fine-polished sheet surfaces upon the sheet-carrying surface 7 of the bending roller.

The bending roller 12 disclosed in Fig. 3 45 has tapered or conical end portions 13 adapted to carry the thickened edge portions 14 of glass sheet 1. This allows the thickened edge portions to make the bend on a smaller radius, thus compensating for an increased 50 speed of these edge portions and functioning

somewhat the same as the freely rotatable sleeves 8 previously described in relieving strains in the glass sheet during the bonding operation.

Claims:

1. In an apparatus for drawing sheet glass, a cylindrical roller about which the sheet is deflected from one plane to another, comprising a portion for supporting and drawing the main central portion of the sheet, and freely rotatable portions for supporting the edge portions of the sheet. 55

2. In an apparatus for drawing sheet glass, a roller about which the sheet is deflected from one plane to another, the roller comprising freely rotatable sleeves adjacent its ends for carrying the edge portions of the sheet. 60

3. In an apparatus for drawing sheet glass, a roller about which the sheet is deflected from one plane to another, the roller comprising a central portion and freely rotatable end portions adapted to carry the edge portions of the sheet, the said end portions of the roller being knurled. 70

4. In an apparatus for drawing sheet glass, a bending roll for deflecting the sheet from one plane to another, said roll being provided with independently rotatable end sections which may be rotated at speeds relative to the speed of said bending roll, said end sections being independently rotatable relative to one another. 75

5. In an apparatus for drawing sheet glass, a roller about which the sheet is deflected from one plane to another, the roller comprising a cylindrical central portion for carrying the main body of the sheet, and freely rotatable end portions adapted to carry the edge portions of the sheet. 85

6. In an apparatus for drawing sheet glass, a bending roll for deflecting the sheet from one plane to another, and independently rotatable end sections journaled on said roll. 90

Signed at Charleston, in the county of Kanawha, and State of West Virginia, this 28th day of January, 1924.

CHARLES TRUELOVE.
WILLIAM T. HAIGHT.
